United States Patent Office

Des. 207,430
Patented Apr. 11, 1967

207,430

BOTTLE

James A. Shepler, Toledo, Ohio, assignor to Owens-Illinois, Inc., Toledo, Ohio, a corporation of Ohio

Filed June 6, 1966, Ser. No. 2,561

Term of patent 14 years

(Cl. D58—6)

FIG. 1

FIG. 2

The back is a mirror edge of the front.

The characteristic features of this design reside in the configuration shown in full lines in the drawing.

I claim:

The ornamental design for a bottle, substantially as shown and described.
